United States Patent Office

Des. 190,886
Patented July 11, 1961

190,886

SPOTTING TELESCOPE

James N. Burlin, New York, N.Y., and Henry Dreyfuss,
South Pasadena, Calif., assignors to Bausch & Lomb
Incorporated, a corporation of New York

Filed June 6, 1960, Ser. No. 60,855

Term of patent 14 years

(Cl. D57—1)

FIG. 1

FIG. 2

FIG. 1 is a perspective view of a spotting telescope taken from the objective end showing our new design; and

FIG. 2 is a perspective view thereof taken from the eyepiece end.

The side not shown is the same as the side shown.

We claim:

The ornamental design for a spotting telescope, substantially as shown and described.
